UNITED STATES PATENT OFFICE

102,176

DESIGN FOR AN OPTICAL DISPLAY CABINET

Boris Chaney, Los Angeles, Calif.

Application October 10, 1936, Serial No. 65,241

Term of patent 7 years

To all whom it may concern:

Be it known that I, Boris Chaney, a citizen of the United States, residing at Los Angeles, county of Los Angeles, State of California, have invented a new, original, and ornamental Design for an Optical Display Cabinet, of which the following is a specification, reference being had to the accompanying drawing, forming part thereof.

In the drawing, Fig. 1 is a front perspective view, on an enlarged scale, of the optical display cabinet, showing my design with the top in opened and extended position.

Fig. 2 is a front elevational view, with the top in closed position.

Fig. 3 is a left side elevational view, with the top in closed position.

Fig. 4 is a right side elevational view, with the top in closed position.

I claim:

The ornamental design for an optical display cabinet as shown.

BORIS CHANEY.
